MINOR WATERS, OF NEW ALBANY, INDIANA, AND BENAGE S. JOSSELYN,
OF LOUISVILLE, KENTUCKY.

RAILROAD-SWITCH STAND.

SPECIFICATION forming part of Letters Patent No. 717,956, dated January 6, 1903.

Application filed September 2, 1902. Serial No. 121,745. (No model.)

To all whom it may concern:

Be it known that we, MINOR WATERS, residing at New Albany, in the county of Floyd and State of Indiana, and BENAGE S. JOSSELYN, residing at Louisville, in the county of Jefferson and State of Kentucky, citizens of the United States, have invented a new and useful Railroad-Switch Stand, of which the following is a specification.

10 Our invention relates to railroad-switch stands, and has particular reference to improvements in switch-stands of the rotary type.

The general object of our invention is to 15 simplify the construction of switch-stands, to lessen the cost thereof, and to so arrange the parts as to enable the repairing of the stand without removing the same from its fastening.

Another object of the invention is to provide an automatic or self-locking rotary switch-stand, and, further, to provide a switch-stand which shall have more than ordinary leverage upon the switch and which shall consequently be easy of operation.

25 The particular object of our invention is to provide a simple, cheap, gravity-locking rotary switch-stand having one weak member, which in ease the switch is forced will be the only part damaged and which may be quickly 30 replaced at little expense without removing the stand from the cross-ties.

Our invention consists generally in a rotary switch-stand comprising a base or housing to be secured to the ties, in combination 35 with a rocking shaft having a vertical bearing in said base and provided with a crank for connection with the switch-points, and a weighted lever connected with said shaft within said housing for operating said shaft 40 and said lever being adapted to engage and lock upon said base at the ends of the stroke of the lever to prevent the accidental opening of the switch; and, further, our invention consists in a rotary switch-stand comprising a base or housing in combination with 45 a shaft mounted in said housing connected with the switch-points and having a weak portion adapted to yield to force that is exerted from the switch-points and suitable 50 means for operating said shaft and locking same after each operation.

Our invention also consists in particular constructions and in combination of parts, all as hereinafter more fully described, and particularly pointed out in the claims.

55

The invention will be more readily understood by reference to the accompanying drawings, forming a part of this specification, and in which—

Figure 1 is an outer side elevation of a 60 switch-stand embodying our invention. Fig. 2 is a plan view thereof with the top plate or cover of the stand removed. Fig. 3 is a vertical section substantially on the irregular line $z z$ of Fig. 2, also showing the target 65 and lantern-standard that is secured to the upper end of the rotary shaft; and Fig. 4 is a vertical section of the base or housing on the line $y y$ of Fig. 1.

As shown in the drawings, the main part 2 70 of the base or housing of the switch is provided with the legs 3, which elevate it a considerable distance above the cross-ties 4, on which the switch-stand is fastened, by means of spikes driven in the notches 5 of the feet 75 6 on legs 3. The base or housing is preferably oval-shaped and is completed by the top plate 7, which is secured to the lower part by means of the two bolts 8 8, which may be readily removed when it is desired to 80 lift the top off. The lower part 2 of the base is provided with the vertical box or bushing 9, that is preferably integral with said part, being joined to the inner and outer walls 2' 2" by the integral bridge or web 10. The top 85 7 is provided with a corresponding bearing or bushing 11, concentric with the bushing 9, with a space between them within the housing. The outer side of the top 7 is open to form the slot 12 between the top plate and 90 the upper edge of the lower portion 2. At the ends of this slot the lower portion is provided with the deep notches 13 13 to receive the switch-lever, hereinafter described.

14 is the rocking or rotary shaft of the device. The lower portion of this fits the bushing or bearing 9 in the part 2, which is bored out to receive it. The upper portion 14' of the crank-shaft is of less diameter than the lower portion and fits the bearing 11 in the 100 top plate. Between the large and small portions of the shaft is the square portion 14" of

the shaft, lying between the bushings 9 and 11, and whereto the switch-lever is connected. The square portion of the shaft measured diagonally equals the diameter of the lower portion of the shaft 14, so that the shaft may be inserted from the bottom of the base. The switch-lever is in two parts 15 and 16. The part 15 fits between the adjacent ends of the bushings 9 and 11 and is provided with a square hole to fit over the square portion 14' of the crank-shaft. This is first placed in position and then the shaft is thrust upward through the base and when in proper position is secured by means of the set-screw 17 in the part 15, and which sets against one of the faces of the square portion of the shaft. The inner end of the part 16 is a yoke 16', that fits over the end of the part 15 and is connected thereto by the pivot pin or bolt 18. The outer end of the lever is provided with a weight 16" and handle 16"". The lever operates in the slot 12 of the base and fits the notches 13, upon dropping into one of which the lever serves to firmly lock the shaft 14 against rotation. The outer end of the lever 16 is preferably formed or bent so that it will be parallel with the ground when the lever is at rest in one of the notches 13. The shaft 14 is turned to fit the bearings neatly and on its lower end is provided with the switch-operating crank 19, which is arranged at substantially right angles to the operating-lever. The connection to the switch-points of the switch is made by the usual rod 20, the end only of which is shown in the drawings. The shaft 14 is preferably of wrought metal, and the crank 19 is preferably welded thereto and is weaker than the shaft, so that in case force is exerted upon it when the shaft is locked by means of a notch 13 and the lever the force exerted will twist, bend, or break only the crank 19. In other words, if a train should run through the switch when closed against it the crank being much weaker than any other part of the stand will be the only part damaged, and this damage may be quickly repaired by loosening the set-screw 17, so that the shaft will drop out of the base and admit of the insertion of a new one in its place. The height of the base above the ties plus the space between the ties permits this to be done easily. The upper end of the shaft 14 is made to fit the lower end of the target and lantern stem or standard 22, that is secured to it by set-screw 23. A distinct advantage is secured by the employment of the heavily-weighted switch-lever, which absolutely prevents the accidental throwing of the lever by shocks communicated to it by a train passing over the switch. At the same time the weight does not hinder the operation of the switch, as the weight of the lever is carried by the upper edge of the lower portion of the base during the time that the lever is being thrown from one notch to the other to open or close the switch.

It is obvious that a simple lever may be sub-

stituted for the jointed lever shown in the drawings, also that the base or housing may be a single casting and that numerous modifications of our invention may be made without departing from the spirit thereof, and we therefore do not confine the invention to the specific construction herein shown and described.

75

Having described our invention, we claim as new and desire to secure by Letters Patent—

1. The rotary switch-stand comprising the base or housing provided with a vertical shaft-bearing, in combination with the crank-shaft arranged therein and having a weak or yielding crank portion for connection to a switch-point and the operating and locking lever connected to said shaft, substantially as described.

80

2. The rotary switch-stand comprising the low base or housing having a horizontal slot and vertical notches in its side, in combination with the short vertical shaft journaled in said base, said shaft having a polygonal portion within said base, and the operating-lever secured to the polygonal portion of said shaft and comprising two parts that are pivotally connected within said base, substantially as described.

85

3. The rotary switch-stand comprising the low base or housing provided with suitable legs and having the horizontal slot in its side, the vertical shaft journaled in said base and having a suitable switch connection and the operating-lever extending through said slots and secured to said shaft and supporting the same for operation, substantially as described.

90

4. In a rotary switch-stand, the low base or housing comprising the lower part 2 and the top 7, slotted and notched as described, and each containing a shaft journal or bearing, in combination with the short crank-shaft arranged in said bearings and provided with the polygonal intermediate portion within said base, and, the operating-lever attached to said polygonal portion of the shaft, substantially as described.

105

5. In a rotary switch-stand, the base or housing comprising the part 2 provided with legs and having the integral bushing 9 and the top 7 provided with a bushing 11 and suitably secured upon said part 2, said parts being provided with a slot 12 and the notches 13, in combination, with the shaft 14 journaled in said bushings 9 and 11 and provided with a polygonal intermediate portion and having the crank upon its lower end, the operating-lever comprising the part 15 secured to said polygonal portion of the shaft and the weighted part 16 pivoted to said part 15 within said base or housing, substantially as described.

115

6. The rotary switch-stand comprising the base or housing provided with a vertical shaft-bearing, the crank-shaft arranged in said bearing, the jointed lever having its inner end secured upon said shaft within said base,

120

125

130

135

means for locking said lever upon said base and the crank of said shaft being the weakest portion of the device, substantially as and for the purpose specified.

5. 7. In a rotary switch-stand, the base or housing provided with the slot 12 and the notches 13 in its side and having a vertical shaft-bearing, in combination with the crank-shaft 14 arranged in said bearing and provided
 10 with the crank 19 and the polygonal portion 14", the target arranged upon the upper end of said shaft and the operating-lever comprising the weighted portion 16 and the short arm 15, pivotally joined within said base, 15 said part 15 fitting said polygonal portion of the shaft and the set-screw 17 whereby said shaft is supported in the base, substantially as described.
8. In a rotary switch-stand, the low hollow base or housing provided with the horizontal slot 12 and the notches 13, 13, in one side and provided with bearings or bushings 9 and 11, in combination with the short vertical crank-shaft arranged in said bearings and provided
 25 with a crank on its lower end, the operating-lever having a weighted outer end and having its inner end secured to said crank-shaft between said bearings 9 and 11, said lever being adapted for vertical movement in said
 30 notches 13 and slot 12 and adapted to fall into said notches, substantially as described.

9. In a rotary switch-stand, the low base of less height than width and provided with the integral bearings 9 and 11, and also having the horizontal slot 12 and the notches 13, 13, in its side, in combination with the crank-shaft 14 having an upper end of reduced size,

held in said bearing 11, the weak crank upon the lower end of said shaft and the operating and locking lever 16 movable in said slot and 40 having its inner end attached to said shaft between the bearings 9 and 11, substantially as described.

10. The rotary switch-stand comprising the oval body provided with the bearings 9 and 11, the side slot 12 and notches 13 and also having the short legs 3 provided with feet to be secured upon the ties, in combination with the short shaft 14 held in said bearings 9 and 11 and provided with a crank on its lower end 50 and a target-step on its upper end and the weighted lever 16 jointed within said base, and having its inner end attached to said shaft between said bearings 9 and 11, substantially as described.

11. In a rotary switch-stand, the low base or housing comprising the lower and upper parts 2 and 7 of substantially the same horizontal configuration, said upper part being provided with the slot or recess 12 and said lower part having the notches 13, in combination with the short crank-shaft 14 journaled in said lower and upper parts and the operating-lever 16 having its inner end secured upon said shaft between said upper and lower 65 parts, substantially as described.

In testimony whereof we have hereunto set our hands, in the presence of two subscribing witnesses, this 29th day of August, 1902.
